United States Patent Office

Des. 184,524
Patented Mar. 3, 1959

184,524

BOTTLE

Arnold I. Lorenzen, Toledo, Ohio, assignor to Owens-Illinois Glass Company, Toledo, Ohio, a corporation of Ohio

Application October 28, 1958, Serial No. 53,194

Term of patent 14 years

(Cl. D58—8)

Fig. 1 is a side elevational view of a bottle showing my new design.

Fig. 2 is an end elevational view.

Fig. 3 is a top plan view.

Fig. 4 is a sectional elevational view taken along the line 4—4 of Fig. 2.

The side and end not shown are the same as the side and end shown.

I claim:

The ornamental design for a bottle, substantially as shown and described.
